UNITED STATES PATENT OFFICE

FRED ASHWORTH, OF BEVERLY, MASSACHUSETTS, ASSIGNOR TO UNITED SHOE MACHINERY CORPORATION, OF PATERSON, NEW JERSEY, A CORPORATION OF NEW JERSEY

FEEDING MECHANISM

Original application filed May 19, 1920, Serial No. 382,558. Divided and this application filed November 23, 1923. Serial No. 676,585. Renewed February 10, 1931.

This invention relates to feeding mechanism for sewing machines.

The object of the invention is to simplify and improve the construction and mode of operation of feeding mechanism for sewing machines and more particularly to improve the construction and arrangement of the parts which move the work feeding devices in the line of feed. The several features of the invention are designed primarily for use in lock stitch outsole shoe sewing machines and are herein illustrated and described as embodied in the lock stitch outsole shoe sewing machine fully disclosed in applicant's pending application Serial No. 382,558, filed May 19, 1920, of which the present application is a division.

In the drawings illustrating a sufficient portion of the machine to enable the invention to be understood, Fig. 1 is a right side elevation of the head portion of the machine; Figs. 2 and 3 are sectional plan views taken on the lines 2-2 and 3-3 respectively of Fig. 1; and Fig. 4 is a detail sectional view 25 of a portion of the work feeding mechanism taken on the line 4-4 of Fig. 2.

In the sewing machine illustrated in the drawings, the work is fed by means of a work support and presser foot while the needle and awl are out of the work. At the completion of the feeding operation the awl is actuated to pierce the work and as the awl retracts the needle closely follows the awl through the work. During the feeding operation and during the described movements of the awl and needle, the work is firmly clamped on the work support by the presser foot. At the limit of the work piercing stroke of the needle, the pressure of the presser foot on the work is relieved and the presser foot and work support are returned to their initial position whereupon the presser foot is again caused to clamp the work firmly on the work support. As the needle is in the work during the back feeding or retraction of the work support and presser foot, there is no danger of the work becoming dislodged by the work support and presser foot being dragged over the work, and the needle is supported at this time

by the needle guide which is advanced to a position in engagement with the work. When the work support and presser foot have been retracted and the presser foot is caused to clamp the work on the work support, the loop drawing stroke of the needle is initiated.

The construction of the work support and presser foot and their actuating mechanism is such that there is no danger of any back lash occurring even when these parts become worn with use. The feeding of the work by means of the work support and presser foot permits the awl and needle to be in alignment at all times so that there is no danger of the needle failing to accurately enter the hole made by the awl as frequently occurs in machines in which the awl is employed to feed the work.

The work support is indicated at 2 and the presser foot is indicated at 4 (Figs. 1 and 3). The work support is shaped as usual to enter the crease between the welt and the upper and to cooperate with an edge gage 6 to guide the work. The work support is provided with the usual slot 8 through which the needle and awl work and through which a fudge or channel knife 10 for the welt extends. The work support is centrally formed on a curved bar 12, the ends of which are secured to arms 14 projecting forwardly 70 from a work support carrier 16. The arms 14 are spaced a distance apart to permit the looper 20 and parts of the actuating mechanisms for the needle and awl to operate between them.

In order that the work support may be actuated to feed the work, the carrier 16 is pivotally mounted on a vertical pin 22 supported by the frame of the machine and spaced at a distance from the end of the work support. The forward end of the carrier 16 is supported by means of a bracket 24 that is provided with a flattened surface with which flattened surfaces formed on the under sides of the arms 14 are in sliding engagement. In 80 order to move the presser foot 4 laterally with the work support to feed the work, it is formed on the end of a lever 26 which is pivotally mounted on an upright bracket 28 projecting from one of the arms 14. 85 100

The carrier is moved about its pivot to feed the work by means of horizontally reciprocating blocks 30 which are pivotally mounted on the ends of a vertical pin 32. The lower block 30 engages a radial groove 34 formed in the carrier 16 and the upper block 30 engages a groove 36 in a relatively fixed block 38, the groove 36 being at an angle to the groove 34. With this construction, it will be understood that by actuating the pivot pin 32 to move the blocks 30 longitudinally of the grooves a lateral feeding movement will be imparted to the work support and presser foot. The pivot pin 32 is actuated to impart the desired feeding movements to the work support and presser foot by means of a link 40 on the forward end of which the pivot pin is formed. The rear end of the link 40 is pivotally connected to an arm 41 secured to the upper end of a vertical rock shaft 42 mounted in the frame. An arm 43 is secured to the lower end of the rock shaft 42 and is provided with a cam roll which engages a groove in a cam disk 44 carried by a driving shaft 46 of the machine.

In order to adjust the length of the feed, the grooved block 38 is adjustable to vary the relative angular positions of the grooves 34 and 36. The block 38 is pivotally mounted by means of a stud 48 projecting from the top thereof engaging a socket bearing in the frame of the machine, and its rear end is pivotally connected to the bifurcated end 35 of a sleeve 50. The other end of the sleeve 50 is split and embraces the rear end of a rod 52, the sleeve being securely clamped to the rod by means of a bolt 54. The rod 52 is screw-threaded through a sleeve 56 mounted 40 to turn in a bearing in the frame and held from longitudinal movement by nuts 58 threaded on its inner end and by a pinion 60 secured to its forward end. By turning the sleeve 56, the block 38 may be adjusted to 45 vary the length of the feed. In order that the operator may conveniently effect such adjustment of the block 38, the sleeve is adapted to be turned by means of a hand lever 62 secured to the right hand end of a 50 rock shaft 64 mounted in the frame. The connection between the sleeve 56 and the hand lever 62 comprises a gear segment 66 engaging the pinion 60, which gear segment is formed on the end of an arm secured to 55 the rock shaft 64. The grooved block 38 is adapted to be adjusted independently of the hand lever 62 to vary the length of the feed. This may be accomplished by loosening the clamping bolt 54 and turning the rod 52 in 60 the sleeve 56, a screw-driver slot being provided in the end of the rod for this purpose.

The invention having been thus described, what is claimed is:—

1. A sewing machine having, in combination, stitch forming devices, work feeding

means comprising a laterally movable work support, a presser foot cooperating therewith, and means for moving the work support laterally to feed the work comprising a member having a groove, a block moving back and forth lengthwise in said groove, means acting automatically to move the block during each stitch forming cycle of the machine and connections between said block and work support to transmit the movement of the block lengthwise in the groove to the work support to feed the work.

2. A sewing machine having, in combination, work feeding means comprising a laterally movable carrier having a groove, and means for moving said carrier to feed the work comprising a reciprocating member, a pair of blocks actuated by said reciprocating member, one of the block being mounted to slide in the groove in the carrier, and a member having a groove extending angularly to the groove in the carrier and engaged by the other block.

3. A sewing machine having, in combination, work feeding means comprising a laterally movable work support having a groove, a presser foot cooperating with the work support, and means for moving the work support to feed the work comprising a reciprocating member, a pair of blocks actuated by the reciprocating member, one of the blocks being mounted to slide in the groove in the work support, a guiding member having a groove extending angularly to the groove in the work support and engaged by the other block, and means for adjusting the guiding member to vary the angular position of its groove.

4. A sewing machine having, in combination, work feeding means comprising a laterally movable work support having a groove, a presser foot cooperating with the work support, and means for moving the work support to feed the work comprising a reciprocating member, a pair of blocks actuated by the reciprocating member, one of the blocks being mounted to slide in the groove in the work support, and a guiding member having a groove extending angularly to the groove in the work support and engaged by the other block.

5. A sewing machine having, in combination, work feeding means comprising a pivotally mounted work support, a presser foot cooperating therewith, and means for moving the work support laterally about its pivot to feed the work comprising a member having a groove inclined to the radius of the work support, a block working lengthwise in said groove, and connections between said block and work support for transmitting the lengthwise movement of the block to the work support.

6. A sewing machine having, in combination, work feeding means comprising a pivot-

ally mounted work support, a presser foot co-operating therewith, means for moving the work support about its pivot to feed the work comprising a member having a groove inclined to the radius of the work support, a block working lengthwise in said groove, and connections between said block and work support, and means for adjusting said grooved member to vary the inclination of its groove relatively to the radius of the work support.

7. A sewing machine having, in combination, work feeding means comprising a pivotally mounted work support, a presser foot co-operating therewith, means for moving the work support about its pivot to feed the work comprising a member having a groove inclined to the radius of the work support, a block working lengthwise in said groove, connections between said block and work support, a manually operable lever, and connections between the lever and said grooved member to vary the inclination of said groove relatively to the radius of the work support upon movement of the lever.

8. A sewing machine having, in combination, work feeding means comprising a pivotally mounted work support, a presser foot co-operating therewith, means for moving the work support about its pivot to feed the work comprising a member having a groove inclined to the radius of the work support, a block working lengthwise in said groove, connections between said block and work support, a manually operable lever, and connections between the lever and said grooved member to vary the inclination of said groove relatively to the radius of the work support upon movement of the lever, the connection between the lever and said grooved member having provision for adjustment to vary said inclination of said groove independently of the lever.

9. A sewing machine having, in combination, stitch forming devices, work feeding means comprising a laterally movable carrier having a groove, a stationary member having a groove set at an angle to the groove in the carrier, means engaging both grooves, and mechanism acting automatically during each stitch forming cycle of the machine to reciprocate said means in the grooves to move the carrier laterally to feed the work.

10. A sewing machine having, in combination, work feeding means comprising a work support, a carrier for the work support pivotally mounted to permit a feeding movement of the work support, a presser foot co-operating therewith, a support for the carrier intermediate the pivot and the work support on which the carrier slides and means for imparting a swinging movement to the carrier about its pivot to feed the work.

11. A sewing machine having, in combination, work feeding means comprising a work

support, a carrier for the work support pivotally mounted to permit a feeding movement of the work support, a presser foot mounted on the carrier to cooperate with the work support, and a support for the carrier intermediate the pivot and the work support on which the carrier slides.
